DRUM

Robert W. Livingston, East Rochester, N. Y.

Application October 28, 1948, Serial No. 57,015

7 Claims. (Cl. 84—412)

1

The present invention relates to musical instruments and more particularly to drums. In a still more specific aspect, the invention pertains to bass drums.

The conventional bass drum is twenty-four inches or more in diameter. It is extremely bulky; and it is awkward to carry and to transport.

At different times in the past proposals have been made for building collapsible drums with the idea that the collapsed drum would occupy less linear space when collapsed than when in operative position, and accordingly would be easier to transport. In all of these prior proposals, of which I am aware, the drum was reduced in dimension only linearly by collapsing it. Its dimensions remained conventional when in operative position; and its diameter was of conventional size even when the drum was collapsed. It was still a difficult instrument to transport. Moreover, with the prior types of collapsible drums, the collapsible feature could be obtained only with a sacrifice in tonal qualities and with deficiencies in drum structure.

One object of the present invention is to provide a collapsible type drum of sturdier, more practical construction than previous proposals for such drums.

Another object of the invention is to provide a drum, which may be collapsed so that it will occupy considerably less space than its operative position, but which, when in operative position, will have the same tonal qualities as a conventional, non-collapsible drum of the same character.

A further object of the invention is to provide a drum, which, when in operative position, will be of smaller diameter than a conventional drum for the same purpose, and which can be collapsed linearly into still further reduced size.

Another object of the invention is to provide a bass drum, which is made of parts that can be telescoped into one another, and which has a diameter considerably less than the diameter of the conventional bass drum and which, when collapsed, will have but little more than the length of such a drum, so that it can be carried and transported readily.

Still another object of the invention is to provide a telescoping type drum, the inside of which can be used, when collapsed, for storage purposes for carrying music, pedestals, pedals and other equipment of the drummer.

Other objects of the invention will be apparent hereinafter from the specification and from the recital of the appended claims.

2

In the drawings:

Fig. 1 is a side elevation showing a collapsible drum built according to one embodiment of this invention in extended position and set up for use;

Fig. 2 is a fragmentary longitudinal sectional view of the extended drum on a somewhat enlarged scale;

Fig. 3 is an end elevation looking at the drum from the left hand end of Fig. 1;

Fig. 4 is a side elevation showing the drum in collapsed position;

Fig. 5 is a fragmentary longitudinal sectional view of the drum in collapsed position;

Fig. 6 is a sectional view on the line 6—6 of Fig. 1 looking in the direction of the arrows; and

Fig. 7 is a sectional view on the line 7—7 of Fig. 1 looking in the direction of the arrows.

Referring now to the drawings by numerals of reference, it will be seen that the drum illustrated comprises two outside shells 10 and 11 and an intermediate tube or cylinder 12. The tube or cylinder 12 is adapted to slide and telescope within the shell 11. It may be made integral with the shell 10, but is preferably formed as a separate part and rigidly secured to the shell 10 by bolts 13 and nuts 14. A rubber gasket or ring 15 is interposed between the shell 10 and cylinder 12 to form an air-tight connection between these parts when the drum is in use. A rubber gasket or ring 16 is glued or otherwise secured in the shell 11 to engage the periphery of the cylinder 12 to provide an air-tight seal between these two parts.

The skins 20 are fastened to the remotely spaced ends of the shells 10 and 11. These may be secured to the shells in conventional manner as by flesh hoops 22 and retaining hoops 23. The requisite tension or pressure on the skins may be applied in the usual manner by means of hooks 25, which engage the retaining rings 23, and screws 26, which thread into lugs 27 that are formed integral with or fastened in suitable manner to the outsides of the shells 10 and 11.

The shells 10 and 11 with the skins 20 and with the means for securing the skins to these shells constitute the drum heads. The shells 10 and 11 and the cylinder 12 are rigid parts. They may be made of wood or metal or any other suitable material.

When the drum is in use, it is extended as shown in Figs. 1 and 2, the shell 10 being moved away from the shell 11 and the cylinder 12 being pulled out of the shell 11 as far as practical.

When the drum is not in use, the cylinder 12 may be telescoped into the shell 11 until the adjacent

ends of the shells 10 and 11 abut against one another as shown in Figs. 4 and 5. In this telescoped or collapsed condition, the drum can readily be transported.

With the present invention it has been found that not only can the length of the drum be reduced for transportation by its telescoping construction, but that its diameter may also be reduced which has additional advantage as regards both transportation and use. It will be noted that when the drum is extended for use, as shown in Figs. 1 and 2, its lengthwise dimension is considerably greater than its diameter. This feature has been taken advantage of to reduce the overall diameter of the drum.

For instance, as stated previously, a conventional bass drum is twenty-four inches or more in diameter. A size widely used is twenty-four inches in diameter and fourteen inches long. With my drum, these dimensions can be partially reversed. The diameter of the drum can be reduced to fourteen inches when its open length is made approximately twenty-six inches. The somewhat increased length as compared with the diameter of a standard bass drum is provided to compensate for the somewhat reduced diameter at the central portion of my drum due to the difference in diameters between the cylinder 12 and the shells 10 and 11.

A drum made according to the dimensions given has been found to have the same tonal qualities as a conventional bass drum. Because of the reduction in diameter, however, it is a much easier instrument to handle even in use than a conventional bass drum. In non-use, it is extremely easy to transport. It can be telescoped to a linear dimension of approximately nineteen inches. Instead of a big drum twenty-four inches or greater in diameter and fourteen inches or as long, with my invention, the drummer has an instrument only fourteen inches by nineteen inches to transport when it is not in use.

My drum can be made at a reasonable cost. The dimensions can be such, for instance, that the shells of a standard snare drum may be used for my telescoping type bass drum. This materially reduces the cost of manufacture.

When in use, the drum may be held in its open position by lock rods 30 (Fig. 7). There are two of these employed. Each of these is adapted to be inserted through aligned holes in a boss 32, tube 34 and boss 36; and each is adapted to be secured in place by a nut 37 that threads onto its lower end. The bosses 32 and 36 are secured to the outside of the shell 11 by screws 38. The tubes 34 are mounted in aligned openings in the cylinder 12. The rods 30 can be manipulated by handles 39 to thread or unthread them from the nuts 37. The handles 37 are integral with the rods.

In use, the drum may be carried by a strap, around the neck of the drummer. For orchestral use, however, legs 40, 41 and 42 are preferably provided to support the drum. The leg 40 may be secured to the shell 10 by a hinge 43 so that it can be folded back against the shells 10 and 11, as shown in Fig. 4, when the drum is not in use. The legs 41 and 42 are adapted to be removably secured by fastening screws 44 in brackets 45 that are adapted to be clamped to the retaining hoop 23 and secured in position by the clamping screws 46.

When the drum is not in use, the legs 41 and 42 are detached from the drum. They may be stored inside of the collapsed drum. In fact, the

collapsed drum may be used for storage of music and of various other articles including the fastening rods 30, for when the fastening rods are detached from the drum, access is had to the space inside of the drum. The case or covering jacket, in which the drum is transported will prevent the drum sections from coming apart.

Fig. 1 shows the drum set up for use in a swing type orchestra. The drum stick 50 is here mounted at one end of the drum for operation by a foot-treadle 52. The drum stick is pivotally mounted upon a pedestal 53; and the pedal supporting plate 54 is clamped to this pedestal which, in turn, is clamped to the foot 40 by a clamp designated generally at 55. A link 51 connects the drum stick with the foot-treadle.

While the invention has been described particularly in connection with use as a bass drum, it will be understood that it is applicable to all types of drums. It will further be understood that while the invention has been described in connection with a particular embodiment thereof, it is capable of further modification, and the present application is intended to cover any variations, uses, or adaptations of the invention following, in general, the principles of the invention and including such departures from the present disclosure as come within known or customary practice in the art to which the invention relates and as may be applied to the essential features hereinbefore set forth and as fall within the scope of the invention or the limits of the appended claims.

Having thus described my invention, what I claim is:

1. A collapsible bass drum comprising two heads, a rigid tubular section which is secured to one of said heads and is adapted to telescope directly into the other, said drum, when extended having a greater length than diameter, and means for detachably locking the tubular section to said other head when the drum is extended.
2. A collapsible drum comprising two heads, a rigid tubular section which is secured to one of said heads and is adapted to telescope directly into the other, said drum, either when extended or collapsed having a greater length than diameter, and means for detachably locking the tubular section to said other head when the drum is extended.
3. A collapsible drum comprising two heads, a rigid body section which is secured to one head and is adapted to telescope into the other head, the diameter of the drum being less than the diameter of a conventional rigid drum for the same use but the length of said drum, when extended, being sufficiently greater than the length of said conventional drum so that the volume of the drum, when extended, will equal approximately the volume of the conventional drum whereby the collapsible drum may possess substantially the same tonal qualities as said conventional drum, and means for detachably locking the tubular section to said other head when the drum is extended.
4. A collapsible drum comprising two heads, a rigid body section which is secured to one head and has direct telescoping relation with the other, and means for locking the drum in open position comprising a pair of rods, each of which is adapted to be passed through aligned openings in one of the heads and said body section.
5. A collapsible drum comprising two heads, a rigid body section which is secured to one head and has direct telescoping relation with the other,

and means for locking the drum in extended position comprising a pair of rods, each of which is adapted to be passed through a hole in a boss formed on the head, a tube mounted in the body section, and a hole in a second boss formed on the head, the bore of said tube being aligned with the holes in the bosses.

6. A collapsible drum comprising two heads, a rigid body section which is secured to one head and has direct telescoping relation with the other, and supporting legs secured to each of the two heads at the same side of the longitudinal axis of the drum and cooperating to support said drum on its side.

7. A collapsible drum comprising two heads, a rigid tubular body section secured to one head and having direct telescoping relation with the other head, a supporting leg secured to one head at one side of the longitudinal axis of the drum,

a separate supporting leg secured to the other head at the same side of said longitudinal axis, said drum, either when extended or when collapsed having a greater length than diameter, and means for releasably locking the tubular section to said other head when the drum is extended.
